UNITED STATES PATENT OFFICE.

MAX RACHLIN, OF NEW YORK, N. Y., ASSIGNOR TO PATENTED METALWARE CORPORATION, OF BROOKLYN, NEW YORK, A CORPORATION OF NEW YORK.

GUTTER-HANGER.

1,397,329.

Specification of Letters Patent. Patented Nov. 15, 1921.

Application filed November 20, 1920. Serial No. 425,424.

To all whom it may concern:

Be it known that I, MAX RACHLIN, a citizen of Russia, and resident of the city of New York, in the county of Kings and State 5 of New York, have invented certain new and useful Improvements in Gutter-Hangers, of which the following is a specification.

The present invention relates to improvements in gutter-hangers, that is to say to devices for supporting roof gutters.

One of the objects of the invention is to provide a gutter-hanger, which is extremely simple in construction, durable in use and capable of manufacture on a commercial 15 scale, or in other words one which is not so difficult to make as to be beyond the reasonable cost of such a contrivance.

Another object of the invention is to produce a gutter-hanger, including a strap portion wholly surrounding the gutter and so shaped that it prevents effectively a tilting movement of the gutter on the supporting brackets connected therewith.

With these and other objects in view, 25 which will more fully appear as the nature of the invention is better understood, the same consists in the combination, arrangement and construction of parts hereinafter described, pointed out in the appended 30 claims and illustrated in the accompanying drawings, it being understood that many changes may be made in the size and proportion of the several parts and details of construction within the scope of the appended 35 claims, without departing from the spirit or sacrificing any of the advantages of the invention.

One of the many possible embodiments of the invention is illustrated in the accompanying drawings, in which:—

Figure 1 is a side elevation of a gutter-hanger constructed in accordance with the present invention; Fig. 2 is a central vertical section taken through a portion thereof, on 45 a larger scale; Fig. 3 is a perspective view of the meeting ends of the strap portion of the hanger; Fig. 4 is a vertical section taken through one of the ends of the strap with an extension piece thereon; and Fig. 5 is a top 50 plan view of the other end of the strap, also with an extension piece in position thereon.

Referring now first to Figs. 1 to 3, inclusive, of the drawings, the numeral 10 indicates a roof gutter, the outer edge of which 55 is provided with a bead 11, as usual in

constructions of this type, while its inner edge 12, adjacent the wall of the building, is plain. For supporting this gutter in proper relation to the roof 13 of the building, there is provided a plurality of hangers, spaced apart a suitable distance, each of said hangers including a strap portion 14, which surrounds transversely the gutter, and a bracket 15, attached to the said strap and the roof.

The strap 14, made of a single piece of 65 metal, includes a curved gutter embracing portion 16, having a hook shaped bend 17 at one of its ends, said bend fitting over the bead 11 of the gutter. The opposite end of the gutter embracing portion of the strap is 70 bent back upon itself, as shown at 18, and fits over the plain end 12 of the gutter, the downwardly bent section 18' of the bend 18 being spaced from the body portion thereof, for a purpose which will appear hereinafter. 75 The hook-shaped bend 17 of the strap is shaped so as to engage and be partly closed around the bead 11 of the gutter, the inner end of the hook being joined to a bar section 19, which extends horizontally and transversely of the gutter. This bar is substantially U-shaped in cross-section, as clearly appears from Figs. 1 to 3, inclusive, of the drawings, its free end 20 being flat and substantially triangular in configuration. The 80 bar section 19 is disposed within the gutter, its flat end being bent upward and located between the downwardly bent section 18' of the strap and the plain edge 12 of the gutter, it extending through a transverse slot 21 in 85 the bight of the bent portion 18, and being bent outward horizontally, as shown at 22, against the said bight.

In the downwardly bent portion 18' of the strap is provided an aperture 23, which 90 is in alignment with apertures 24 and 25 in the flat end of the strap and the body portion of the said strap, respectively, when the ends of the strap are engaged in the manner above described and as shown in Figs. 1 and 100 2 of the drawings. A nail 26 is driven through these apertures and the adjacent portion of the wall of the gutter, said nail being driven into the wall 27 of the structure, upon which the gutter is to be positioned. The pointed outwardly extending portion 22 of the strap end may also be 105 driven into the wall, as shown in Fig. 1 of the drawings.

The bracket 15 is joined with the bar sec- 110

tion 19 by a rivet 28, or otherwise, it including an upwardly extending portion 29 and an outwardly projecting section 30, which is secured by nails 31, or otherwise, to the roof 13, from which the rain water is to be carried off.

The straps 14 are, preferably, formed by stamping operations and are furnished to the user as substantially straight strips, containing the hook-shaped bends 17 and having attached thereto the brackets 15. In use, the hook-shaped bend 17 is engaged with the bead 11 of the gutter, and the gutter embracing portion 16 bent around the same, after which the bend 18 is formed. The bar 19 is then extended across the gutter and its flat end 20 is engaged with the bend 18 and caused to extend outward, as shown in Fig. 1 of the drawings. The nail 26 is then driven through the strap and gutter into the wall, after which the bracket 15 is fastened to the roof.

Inasmuch as the straps wholly surround the gutter and the pointed ends 22 of the straps are driven into the building wall, the gutter is prevented from tilting on the brackets.

In order to permit the hanger to be used on gutters of various sizes, the length of its strap is made adjustable. A construction of this type is shown in Figs. 4 and 5 of the drawings, differing from the one above described in that extension pieces 32 and 33 are hooked into the ends of the strap. These extension pieces are formed like the strap ends described in connection with Figs. 1 to 3, inclusive, of the drawings, their ends terminating in hooks 34 and 35, respec-

tively, the hook 34 engaging any one of a series of openings 36 in the gutter embracing portion 16, while the hook 35 is adapted to engage any one of a series of openings 37 in the bar section 19. Otherwise the construction and operation of the elements are the same as of those described in connection with Figs. 1 to 3, inclusive, of the drawings.

What I claim is:—

1. A gutter-hanger comprising a strap of metal surrounding transversely the gutter, and a bracket attached to said strap, said strap including a curved gutter embracing portion having a hook-shaped section on one of its ends fitting over the bead of the gutter, the opposite end of said curved portion being bent back upon itself and extending downwardly into the gutter, the bight of said bent portion being provided with a transverse slot, said hook-shaped section extending into the gutter and merging into a horizontally extending transverse bar having a flat upwardly projecting end located between the inner face of the gutter and the downwardly extending portion of said bend, said flat portion projecting through said slot and being then bent outward substantially horizontally against said bight, said bracket being attached centrally to said bar.

2. In a gutter-hanger according to claim 1, said bar being substantially U-shaped in transverse cross-section.

Signed at New York, in the county of New York and State of New York, this 10th day of November, A. D. 1920.

MAX RACHLEN.
